Specification for Design.

Patented May 13, 1919.

Application filed February 20, 1919. Serial No. 278,301. Term or patent 3½ years.

To all whom it may concern:

Be it known that I, FREDERICK E. GREENE, a citizen of the United States, residing at Mount Vernon, Westchester county, State of New York, have invented a new, original, and ornamental Design for Automobile-Trimming and the like, of which the following is a specification, reference being had to the accompanying drawing, forming a part thereof.

In said drawing:

Figure 1 is an edge view to illustrate the contour of my automobile trimming.

Fig. 2 is a plan view illustrating the design in detail.

I claim—

The ornamental design for an automobile trimming and the like, substantially as shown.

FREDERICK E. GREENE.
